(57) **CLAIM**

The ornamental design for a dog grooming loop cover, as shown and described.

DESCRIPTION

FIG. 1 is a bottom perspective view of a dog grooming loop cover showing our new design.

FIG. 2. is another perspective view thereof.

FIG. 3 is yet another perspective view thereof.

FIG. 4 is a top view thereof.

FIG. 5 is a bottom view thereof.

FIG. 6 is a front view thereof. The back view is a mirror image of the front; and,

FIG. 7 is a left side view thereof. The right side view is a mirror image of the left.

The broken lines in the drawings indicate environmental structure that forms no part of the claimed design.

1 Claim, 4 Drawing Sheets
